UNITED STATES PATENT OFFICE.

ARTHUR M. WILLARD, OF CHICAGO, ILLINOIS.

SEAL-PRESS.

1,346,150.

Specification of Letters Patent. Patented July 13, 1920.

Application filed March 24, 1919. Serial No. 284,711.

To all whom it may concern:

Be it known that I, ARTHUR M. WILLARD, a citizen of the United States, residing at Chicago, in the county of Cook and State of Illinois, have invented certain new and useful Improvements in Seal-Presses, of which the following is a specification.

This invention relates to a press, through means of which a seal or other impression 10 may be applied to paper, and it has for its object to provide a construction of press which will be of lighter construction and which will particularly avoid the use of the heavy plunger and its bearing as heretofore employed in such presses; also to provide a 15 construction in which the member which carries the movable die will be presented to its mating die with great accuracy and yet with sufficient freedom of yielding that will 20 render the die self leveling with respect to any irregularity in the thickness of the material on which the imprint is being made. A further object is to provide a construction 25 of seal press that will adapt the press to be made of stamped or pressed metal.

To these ends, one feature of the present invention consists in mounting the movable die of a seal press upon a substantially straight, plate-spring radius-arm supported 30 upon the bed of the press in a manner to assume substantial parallelism throughout when the dies are impressing, and at a point sufficiently remote from the impression area to enable the movable die to normally approach its mating die in a position substantially parallel thereto; the radius-arm being rigid in all directions in a plane perpendicular to the direction of its impressing movement so that accurate registry of the 35 two dies is insured, but being transversely and torsionally resilient in directions transverse to its plane so that the moving die may yield sufficiently to compensate for any unevenness in the thickness of the material 40 on which the impression is to be made, for instance, such as would develop from partial insertion of a paper, or the insertion of a paper that is unequally supported by papers beneath it; the radius-arm being provided with an elevated boss centered above 45 its impression die, and upon which the imprinting pressure is centrally imposed so as to evenly distribute such pressure at different circumferential points on the die, notwithstanding such unevenness, leaving the 50 movable die free to compensate therefor;

the imprinting pressure being developed by a cam lever supported between two spaced cheeks or plates which constitute the jaw of the press, and which are spaced apart in a 60 manner to receive the spring-plate radius-arm between them and accurately define its position against lateral displacement relatively to the die carried by the bed of the press.

Another feature of the invention consists in constructing the press with a base struck up from sheet metal and formed with a bed 65 surrounded by a deep stiffening and supporting flange to produce a rigid support 70 for the working parts, with a hollow underside, and closing the underside by means of a bottom plate held in place by resilient tangs struck up from the metal of the bottom plate and fitting snugly within the wall 75 afforded by the flange of the base; also a jaw mounted upon one end of the base and extending upwardly and forwardly therefrom to the opposite end, with space beneath it to receive the moving die and its supporting 80 radius arm and provide for the introduction of the paper to be impressed, said jaw being formed of sheet metal bent into two parallel side arms, connected at the upper forward end by a spacing web, and having their 85 lower rear ends seated upon the base and held thereto by integral tongues of metal passing through the platen of the base, lapped beneath it, and securely riveted to the base; also an operating lever fulcrumed 90 between the upper forward ends of the arms, working in the slot provided between them, and having a camming offset carrying an anti-friction roll which acts upon the movable die to depress it, the operating lever 95 being struck up from sheet metal with a web portion, and a pair of stiffening flanges which receive its fulcrum point and also the anti-friction roller; and said lever carrying at its fulcrum-end a dog movable into position which will cause it to abut against the connecting bar of the jaw and hold the lever 100 in position to keep the die depressed when the press is not in use.

The invention will be fully understood 105 upon reference to the accompanying drawings, in which—

Figure 1 is a vertical longitudinal section and Fig. 2 a side elevation of a seal press embodying the several features of the 110 present invention.

Fig. 3 is a detail sectional view illustrat-

ing the anchorage of the jaw upon the base and the support of the inner end of the flexible radius arm relatively thereto.

Figs. 4 and 4^a are, respectively, an edge 5 view and a top plan view of the closure plate for the bottom of the base.

Figs. 5 and 5^a are, respectively, a plan view and a longitudinal sectional view of the flexible radius arm which carries the 10 movable die; and

Fig. 6 is a top plan view of the press.

1 represents the base which provides the bed of the press and which is preferably stamped from sheet metal, with a deep stiffening and supporting flange 1^a surrounding it and providing a hollow underside to accommodate connecting means employed for mounting parts on the base. The bottom of the base is closed by a removable plate 2, 20 which is preferably of metal and held in place by tangs 2^a struck up from the body of the closure plate and standing in position to fit within the flange 1^a with sufficient snugness to hold the plate in position.

25 3 represents the jaw of the press, which is preferably of sheet metal, bent to provide a pair of arms 3^a spaced apart (see Fig. 6) to provide a slot between them, and connected together at their upper forward ends 30 by means of the cross bar 3^b, while their rear lower ends rest squarely upon the base 1 and are held thereto by means of anchoring tongues 3^c which pass through slots in the base 1 and also through the filler plate 35 1^b beneath which the tongues are folded one upon the other as shown in Figs. 1 and 3, and then secured by a rivet passing through the bed of the base, the filler plate, and the two tongues as shown. By means of this 40 connection with the base and the cross bar at their outer ends, the arms are accurately spaced apart and adapted to serve as cheeks or guide plates for parts mounted between them. The anchoring tongues 3^c are located 45 well forward of the longitudinally extended bearing which the arms of the jaw have upon the base, in order to bring them as near as practicable to the upward stress exerted on the free end of the jaw, and in order to 50 leave the rear heel of the jaw sufficiently offset to resist upward turning movement, which action the press imposes on the jaw.

Mounted upon the base 1 and fitting accurately between the side arms 3^a is a radius 55 arm 4, preferably constructed of a flexible plate, depending upon its own resiliency for its freedom to swing vertically, and rigidly held to the bed at its rear end, as, for instance, by securing it upon the spacing block 60 4^a by means of the bolt 4^b passing through the arm, spacing block, and base. As shown in Fig. 5, the spring plate radius arm 4 has straight parallel sides, and as shown in Figs. 3 and 6, this plate fits accurately between 65 the parallel sides of the arms 3^a; while as

shown in Figs. 1 and 2 the longitudinal dimension of the portion so fitting between the arms constitutes a considerable proportion of the length of the radius arm. Hence, the radius arm is secured against lateral displacement, and the die carried thereby is kept in registry transversely of the bed by means of the arms 3^a, and this greatly facilitates accurate assembly of the parts and maintaining proper registry after they are assembled. At the forward end said radius arm carries a boss 5 formed with a socket 5^a to receive the shank 6^a of the movable die 6. As herein shown, the boss 5 is constructed of a separate piece shouldered upon the free end of the radius arm 4, and having a reduced lower portion extended through and riveted to the arm as at 5^b. The free end of the radius arm is formed with a circular disk-like enlargement (see Figs. 5 and 5^a) 70 to receive the boss 5 and the movable die 6, and this shape together with the cylindrical form of the shank and socket adapt the movable die to be assembled with the radius arm 75 with any desired presentation of the printing characters. Moreover, this circular enlargement of the radius arm is dished or concaved so that when the die is assembled the outer portion of the enlargement will seat upon the die first, and when the disk-like enlargement of the arm is flattened, as it will be by firmly pressing it against the die and in which form it will be retained by the snug fit of the shank of the die in the socket, this outer bearing edge will always 80 remain under sufficient pressure, due to the resiliency of the metal of the disk, to insure a firm frictional hold at a sufficient distance from the center to prevent any turning displacement of the die in the arm. 85

90 Mounted between the upper forward ends of the side arms 3^a of the jaw 3 is an operating lever 7, also preferably pressed from sheet metal in a manner to form vertical flanges 7^a with a connecting web 7^b, said 95 lever being fulcrumed upon a pintle 8 passing through the forward end of its flanges 7^a, and having camming offsets 7^c that receive the roller 9 between them and thereby 100 adapt the lever to develop a downward and 105 forward moment of the camming projection through a relatively short radius from the fulcrum 8 by hand pressure applied at the end of the relatively long radius afforded by the lever 7, and thereby impart to 110 the boss 5, and through it to the movable die 6, a very effective pressure in the direction of the imprint to be made. 115

120 As before suggested, the transverse and torsional flexibility of the radius arm 4 (preferably attained by making said arm in the form of a plate spring) will render the movable die self leveling with respect to the thickness of the material to be impressed, and this function is left free to develop by 130

the above-described method of imposing thrust upon the boss 5.

In order to hold the lever in depressed position when the press is not in use, a locking dog 10 is fulcrumed at 10^a between the flanges 7^a of the lever 7 at a point sufficiently above the fulcrum 8 to develop a distinct forward movement of the dog 10 from the upward swinging of the lever 7, and this dog is provided with a shoulder 10^b which encounters the crossbar 3^b of the jaw 3 whenever the dog is permitted to drop into the position shown in Fig. 1. Through means of a finger-piece 10^c on the dog 10 the forward end of the dog may be raised to a position above the cross bar 3^b, as suggested in Fig. 2, and so leave the lever free to swing upwardly. It will be noted that the journal 9^a of the roller 9 is sufficiently in rear of the fulcrum 8, even when the lever is depressed to its lower limit, to develop an upward moment in the lever from the reaction of the spring radius arm 4, so that the lever will be maintained in the position shown in Fig. 2 by the spring 4 when freed from hand pressure and the detaining dog 10 is released.

While the design selected for illustration is that of a seal suitable for resting upon a support, it is obvious that the several features of the invention are equally applicable to the so-called hand seal, in which the jaw as well as the operating lever is grasped in developing the impressing thrust.

Obviously, the spacing block 4^a is not indispensable to the mounting of the flexible radius arm 4; the latter may by proper deflection, be made to seat directly upon the base 1, and have its outer free end in position to present the die 6 in proper relation to the mating die. It is to be noted that the radius arm is deflected, preferably near its attaching disk, in order to compensate for any angular position which it has reached by the time the dies come together, and so insure normal parallelism between the faces of the meeting dies.

I claim:

1. In a seal press, a rigid bed, a stationary die mounted on said bed, a movable die co-acting with said stationary die, a transversely flexible, but horizontally rigid and longitudinally inextensible, spring plate carrying said movable die at one end thereof, means clamping the face of said plate at the other end thereof, rigidly to the bed, and leaving the plate free to act as a radius arm by its inherent transverse flexibility, but restricting such radius arm action to the portion of said plate outside of its anchorage upon the bed, and means for pressing the dies together.

2. In a seal press, a radius arm carrying a socket at its free end and having the metal surrounding said socket resilient and nor-

mally concaved, and a die mounted in said socket and seated against said concaved face; the metal of the free end of the arm standing under strains of flexure and maintaining contact with the die by its resiliency. 70

3. In a seal press, the combination of a bed carrying a fixed die, a jaw arising from said bed, a radius arm comprising a substantially straight spring-plate carrying a movable die in position to register with the 75 fixed die and firmly anchored at its end remote from the dies, a raised boss centered above the movable die on the radius arm, and an operating lever mounted in the jaw and bearing centrally upon said boss; the 80 radius arm having edgewise rigidity with torsional as well as vertical transverse resiliency.

4. In a seal press, the combination of a bed carrying a fixed die, a jaw arising therefrom, an operating cam lever mounted in said jaw, and a radius arm comprising a spring plate carrying a movable die at one end, firmly anchored at its opposite end, and adapted to receive the cam lever over said 85 movable die; said radius arm having a concaved under face through which it receives the movable die.

5. In a seal press, the combination of a bed carrying a fixed die, a jaw arising therefrom, an operating cam lever mounted in said jaw, and a radius arm comprising a spring-plate carrying a movable die at one end, firmly anchored at its opposite end, and adapted to receive the cam lever over said 95 movable die; said radius arm having a concaved under face through which it receives the movable die, and a pressure boss centered above the concave face of the radius arm and receiving the cam lever. 100

6. In a seal press, in combination with a jaw member and an operating-lever member, a detaining dog carried by one of said members in position to abut against the other of said members and oppose opening 110 movement of the lever.

7. In a seal press, a jaw, an operating lever fulcrumed on the jaw, and a detaining dog carried by the lever in position to abut against the jaw and resist opening movement 115 of the lever.

8. In a seal press, the combination of a jaw comprising a pair of spaced arms connected by a cross bar, an operating lever fulcrumed between the spaced arms adjacent 120 the cross bar, and a detaining dog carried by the lever in position to abut against the cross bar and resist opening movement of the lever.

9. In a seal press, the combination of a 125 jaw comprising a pair of spaced arms and a connecting cross bar, an operating lever fulcrumed between said arms in rear of the cross bar, and a detaining dog movably mounted on the operating lever at a point 130

- which adapts it to encounter the cross bar, and sufficiently above the lever fulcrum to develop a forward moment across the cross bar.
5. 10. In a seal press, in combination with a jaw member and an operating-lever member, a detaining dog carried by one of said members in position to abut against the other of said members and oppose opening movement of the lever; said dog having a finger piece through which to press it out of dogging position.
10. 11. In a seal press, a jaw, an operating lever fulcrumed on the jaw, and a detaining dog carried by the lever in position to abut against the jaw and resist opening movement of the lever; said dog having a finger-piece for lifting it out of engagement with the cross bar, and which rests upon the cross bar to support the dog in engagement with the cross bar.
15. 12. In a seal press, the combination of a base, a jaw arising from said base and comprising a pair of spaced arms individually anchored to the base at their lower ends and spaced apart thereby, and having a connecting and spacing cross bar, and impression and operating mechanism mounted between and guided in their movements by said arms.
13. In a seal press, a base, a jaw arising 30 from said base and extending forwardly over the same, an operating lever fulcrumed at the forward end of the jaw, and impression dies controlled by said lever; said jaw comprising a pair of spaced plates each having a longitudinally elongated seat upon the base at the lower rear end of the jaw and having at the forward portion of its said seat tongues projected through the base and folded upon the underside of the latter to 35 hold the jaw down upon the base; said tongues being carried by the forward portions of the seats of the respective arms of the jaw and leaving the rear portions of said seats extending rearwardly therefrom to resist the lifting force exerted by the lever at the forward end of the jaw.
- 40 Signed at Chicago, Illinois, this 21st day of March, 1919.
- 45 ARTHUR M. WILLARD.
